UNITED STATES PATENT OFFICE.

SCOTT H. HULL, OF OSKALOOSA, IOWA.

DESIGN FOR A HARNESS-D.

SPECIFICATION forming part of Design No. 29,335, dated September 13, 1898.

Application filed August 15, 1898. Serial No. 688,635. Term of patent 14 years.

To all whom it may concern:

Be it known that I, SCOTT H. HULL, a citizen of the United States, residing at Oskaloosa, in the county of Mahaska and State of Iowa, have invented and produced a new and original Design for a Harness-D; and I do hereby declare the following to be a full, clear, and exact description of the same, reference being had to the accompanying drawings, forming a part thereof.

My invention relates to a new and useful design for a harness-D or strap-guide, and is illustrated in the accompanying drawings, in which—

Figure 1 is a front view of a harness-dee embodying my design. Fig. 2 is a rear view of the same. Fig. 3 is an end view, and Fig. 4 is a central vertical section.

The invention consists, essentially, as shown in the drawings, of an elliptical guide-plate A, provided with an approximately oval-shaped slot b, an elongated rectangular base-

plate C, formed with an orifice d, and a shank E, uniting said plates. The lower arm e of this shank is vertically disposed, while the upper arm e' thereof is segment-shaped and extends forwardly and upwardly and terminates at the rear side of the guide-plate A, thus projecting the two plates in different vertical planes, one being disposed in advance of the other, as shown.

The upper and lower edges of the base-plate C are straight and plane-surfaced throughout their entire length.

Having thus described the invention, what is claimed as new is—

The design for a harness-D, as herein shown and described.

In testimony whereof I affix my signature in presence of two witnesses.

SCOTT H. HULL.
